UNITED STATES PATENT OFFICE.

FRED D. HOLDSWORTH, OF CLAREMONT, NEW HAMPSHIRE, ASSIGNOR TO SULLIVAN MACHINERY COMPANY, A CORPORATION OF MASSACHUSETTS.

CONTROLLING MECHANISM.

Application filed September 15, 1925. Serial No. 56,538.

While this invention relates generally to improvements in controlling mechanisms, it is directed more particularly to an improved means for pneumatically controlling power flow to a compressor driving mechanism and to effect load control of the compressor.

In compressor mechanisms it is usual to have means for controlling the compressor load in accordance with receiver pressure and when the compressor is unloaded it is desirable to reduce power flow to the compressor driving mechanism. While this driving mechanism herein specifically takes the form of an internal combustion engine, power flow thereto being controlled by a valve in the intake manifold, yet it will be clear that broadly the driving mechanism could be of any other type such as an electric motor and that power flow thereto would be controlled by any usual mechanism associated with that type of motor. When reloading of the compressor occurs it is desirable that power flow to the motor should have been increased a sufficient time before the compressor is reloaded to enable the motor to have developed sufficient power to carry the full load that is ordinarily suddenly thrust upon the compressor due to quick reloading thereof.

It is accordingly an object of my invention to reduce power flow to the motor when the compressor is unloaded and further to increase power flow to the motor just prior to loading of the compressor. In one specific aspect of the invention I accomplish these objects by controlling the intake manifold valve on an internal combustion engine by a pneumatically actuated mechanism which also controls fluid flow to a usual type of compressor load controlling mechanism. The parts are so arranged that prior to loading of the compressor the engine throttle valve will be opened first, thereby increasing the power developed.

A further object is to provide improved means whereby the engine throttle valve can be controlled independently of compressor unloading, which means, in one specific aspect of the invention, includes means for limiting the closing limit of the throttle valve, thereby permitting predetermined

power flow to the motor while the same is running idle.

In the accompanying drawings I have shown for purposes of illustration two forms which my invention may assume in practice. 55

In these drawings,

Fig. 1 is a side elevation of a portable compressor embodying my invention.

Fig. 2 is a vertical section through the controlling mechanism. 60

Fig. 3 is a sectional view on line 3—3 of Fig. 2.

Fig. 4 is a vertical section of a modified form of controlling mechanism.

Fig. 5 is a fragmentary plan view thereof. 65

For purposes of illustration I have shown my invention embodied in an engine-compressor mechanism such as disclosed in my copending application, Serial No. 706,583, filed Apr. 14, 1924, and identical thereto in 70 such respects as the type of compressor unloading mechanism and the general arrangement of parts. Briefly, this outfit comprises a motor 1 preferably of the internal combustion engine type which is adapted through 75 suitable connections to actuate a compressor 2 carrying unloading mechanisms 3 and 4. The unloading mechanism is actuated by pressure fluid flowing from a receiver 5 through pipes 6, 7, 8, 9 and 10 and branch 80 pipes 11 and 12. An unloader pilot valve 13 has communication with the pipes 6 and 7 to permit flow of fluid into the pipe 7 when a predetermined high pressure is had in the receiver 5 and to exhaust the pressure fluid in 85 the pipes 7 and 8 when a predetermined low value is reached.

To control power flow to the motor and to actuate the unloading mechanism a controlling mechanism 15 has communication 90 with the pipes 8 and 9. This controlling mechanism comprises a casing 19 having a cylinder bore 20 within which a piston 21 is reciprocably mounted. A head 22 secured to the cylinder has an opening to receive the pipe 8 which terminates adjacent an annular valve seat forming flange 24. A spring 25 is interposed between the top of the piston and an upper cylinder head 26. The piston has a stop portion 28 engageable with a down- 100

wardly projecting portion 29 of the head 26, while a stem 30 extends upwardly through a bore in the head. Adjustably threadedly mounted upon the stem is a tappet block 31 for engaging one arm 32 of a bell crank which is pivotally mounted as at 33 upon an arm 34 extending upwardly from and carried by the cylinder head 26. The other arm 35 of the bell crank has a series of holes 36 therein to receive adjustably one end of a rod 37 which at its other end is connected to a butterfly valve 16 disposed in the intake manifold of the engine. A spring 38 normally tends to keep the arm 32 in contact with the member 31, but it will be clear that if for any reason the operator desires to increase power flow to the engine he may move the bell crank to actuate the butterfly valve without affecting the controlling mechanism.

When the receiver pressure reaches a predetermined high value, the pilot valve 13 will permit fluid to flow through the pipes 7 and 8, thereby forcing the piston 21 from its seat 24 to move the butterfly valve towards its closing position. Fluid for actuating the unloading mechanisms 3 and 4 is controlled by the piston 21 which opens a passage 40 formed in a projecting boss 41 carried by the cylinder 19. A passage 42 leading to the pipe 9 and to an exhaust port 43 is adapted to have communication with the passage 40 by way of a passage 44 which is controlled by a valve 45. Access to the valve 45 is had through an opening normally closed by a removable plug 46.

In operation, assuming that receiver pressure has reached its predetermined high value, fluid will flow past the unloading valve 13 and raise the piston 21 to move the intake valve to closing position and also uncover and cover respectively the passages 40 and 42. When the passage 40 is uncovered, which cannot happen until after the passage 42 has been covered, due to the length of the piston 21, fluid pressure will raise the valve 45 allowing fluid to flow to the unloading mechanisms 3 and 4. When receiver pressure has fallen to a predetermined low value, the pipe 8 will be vented to the atmosphere by the pilot valve mechanism 13, thereby allowing the spring 25 to force the piston 21 downwardly upon the seat 24 and thereby permitting the spring 38 to move the intake valve to open position. It will be noted however that the piston 21 travels downwardly a predetermined distance before the passage 42 has communication with the atmosphere as by way of the cylinder 20 and exhaust port 43. Hence the engine throttle valve will be opened prior to the release of the unloading mechanism actuating pressure, thereby giving the engine a chance to increase its speed before the compressor is loaded. While the piston 21 is descending and the passages 42 and 40 are closed and opened respectively, the valve 45

will be seated by the pressure in the passage 42 which is greater than the falling pressure in the pipe 8 and passage 40. This valve thereby constitutes a means cooperating with the piston for effecting an out of phase relation between the loading of the compressor and the speeding up of the engine. When the piston 21 has uncovered the passage 42 the compressor will be fully loaded, but prior to this time the engine will have developed sufficient power for carrying the load.

In Figs. 4 and 5 I have shown a modified form of my invention which differs from the preferred form in the general arrangement of parts and in having the further feature of being able to control the closing limit of the engine throttle valve independently of the controlling mechanism, although it will be clear that this limiting means is readily adaptable to the preferred form.

This controlling mechanism comprises a cylinder 50 having a flanged annular machined portion 51 which is slidably received in a bore 52 of the housing 53. A member 54 forming a cylinder head has a recess 54a which receives an annular portion of the housing 53. The cylinder 50, housing 53, and member 54 may be secured together in any desired manner such as by forced fits or the like. A two-spool piston 55 carries a valve portion 56 and a stem 57 which adjustably carries a tappet 58. A spring 59 is disposed between the piston and a cylinder head 60 which carries an arm 61. A bell crank including an arm 62 to which is attached the engine throttle valve rod 37 is pivotally mounted upon the arm 61 as at 63 while the other arm 64 of the bell crank engages the tappet 58. The valve 56 controls a passage 65 which has communication with a passage 66 and pipe 8, the latter leading from the pilot valve 13. Flow of fluid to the unloading mechanism is permitted after the piston 55 has moved a predetermined distance. Annular grooves 70 and 71 are formed in the periphery of the annular portion 51 and have communication with the cylinder as by radial ports 72 and 73. Grooves 70 and 71 communicate respectively with passages 74 and 75. Communication between these passages as by a passage 76 is controlled by a valve 77 disposed in the passage 74. This valve may be removed as through an opening normally closed by a removable plug 78. The pipe 9 which leads to the unloading mechanism is in communication with the annular groove 71 and is adapted to be placed in communication through it and the interior of the cylinder 50 with an exhaust port 79 leading from the cylinder 50.

To control variably the closing limit of the engine throttle valve a lever 80 pivotally mounted upon the pivot 63 carries a pin 81 engageable with the arm 62. An arm 82 fixed to the lever 80 is adapted to be held as by a wing nut 83 cooperating with a slotted mem-

ber 84 which is pivotally mounted on the cylinder 50 as at 85. The nut 83 when loosened may be moved downwardly or upwardly within the slotted portion of the member 84 and clamped in any desired position, thereby to limit rearward movement of the arm 62 by engagement thereof with the pin 81. A spring 86 normally tends to keep either the arm 62 in contact with the pin 81 or the arm 10 64 in contact with the tappet 58.

Operation of this form of the device is substantially the same as the preferred form in that when receiver pressure reaches a predetermined amount the piston 55 will be 15 moved to close the engine throttle valve and to allow flow of fluid past the valve 77 through the passages 76, 75 and annular groove 71 to the pipe 9. It will be seen, however, that the radial ports 73 will be 20 closed prior to the opening of the ports 72. Reverse movement of the piston 55 is effected by the spring 59 when, due to the receiver pressure reaching its predetermined low value, the pilot valve 13 releases the pressure 25 within the passages 66 and 65 in the lower end of the cylinder. It will be noted that the engine throttle valve will be opened prior to the communication of the port 73 with the exhaust port 79, and that accordingly 30 the engine speed will be increased; so that when the port 73 is opened and actuating pressure for the unloading mechanism released, the engine will have sufficient power to carry the full load. As soon as the pressure 35 in the pipe 8 and passage 66 falls, due to being vented to the atmosphere by the pilot valve 13, the valve 77 will be closed by the pressure in the pipe 9, thereby maintaining the compressor unloaded until the piston un- 40 covers the ports 73 to vent the unloading actuating pressure fluid to the atmosphere through the exhaust port 79. The modified form of the device has the piston preferably disposed in a horizontal position although it 45 will be clear that any other position thereof might be had.

By having an interval of time between opening of the engine throttle valve and loading of the compressor, undue vibration is prevented for it has been found that without this time relation the engine will vibrate considerably due to it being necessary to bring a full load at a relatively low speed up to a normal running speed. Also by having 55 a reduced piston area such as caused by the annular valve seating surface 24 and the reduced valve 56 exposed to the pressure in the line 8 the respective piston will not be moved until substantially full receiver pressure 60 has been created in the line 8. When the pistons have very slightly moved off their seats, fluid will flow to the entire piston area which will create an actuating force far greater than is necessary to move the piston. 65 Accordingly, the pistons will move rapidly

past the controlled passages, thereby eliminating any sluggish action of the controlled elements.

While I have in this application specifically described two forms which my invention may assume in practice, it is to be understood that these forms of the same are shown for purposes of illustration and that the invention may be modified and embodied in various other forms without departing from its spirit or the scope of the appended claims.

What I claim as new and desire to secure by Letters Patent is:

1. A controlling mechanism comprising a controlled element, a cylinder, a fluid responsive piston therein adapted to have operative connection with said element, a conduit for leading pressure fluid to said cylinder, a second conduit leading from said cylinder, the said piston being movable in said cylinder so that in one position the flow of fluid to said second conduit is obstructed by said piston and in another position the flow is permitted, and means for maintaining fluid pressure in said second conduit during release of the actuating fluid pressure for said piston.

2. A controlling mechanism comprising a controlled element, a cylinder, a fluid responsive piston therein mechanically connected with said element, a conduit for leading pressure fluid to said cylinder, a second conduit leading from said cylinder, the said piston being movable in said cylinder so that in one position the flow of fluid to said second conduit is obstructed by said piston and in another position the flow is permitted, and means for venting said second conduit upon predetermined movement of said piston.

3. A controlling mechanism comprising a cylinder with a piston therein, means providing main and auxiliary passages both communicating with said cylinder, said piston being movable in said cylinder so as to permit fluid to flow from said cylinder to said main passage through said auxiliary passage, and means whereby flow of fluid from said main passage to said auxiliary passage is prevented when pressure of the fluid in said auxiliary passage is reduced.

4. The combination with a compressor, a driving motor therefor, and a receiver, of fluid pressure operated unloading means for said compressor, a control for said motor, a conduit for supplying pressure fluid from the receiver to the unloading means to actuate the same, and a valve means in said conduit comprising an element adapted to be displaced by the passage of pressure fluid to the unloading means, said element being mechanically connected to said motor control so as to shift said motor control when pressure fluid is supplied to the unloading means for the compressor.

5. The combination with a compressor and

- a driving motor therefor, of fluid pressure operated unloading means for said compressor, a control for said motor, a conduit for leading fluid compressed by said compressor 5 to said unloading means, a valve means in said conduit comprising an element adapted to be displaced by the passage of pressure fluid to the unloading means, said element being operatively connected to said motor control 10 so as to shift said motor control when pressure fluid is supplied to the unloading means for the compressor, and a check valve to trap fluid which has passed the valve means toward the unloading means.
- 15 6. A controlling mechanism comprising a cylinder, a pair of passages communicating with said cylinder, a passage connecting said other passages, a check valve for permitting flow in one direction through said connecting passage but preventing flow in the opposite direction, and a piston movable in said cylinder to control said pair of passages.
- 20 7. A controlling mechanism comprising a cylinder, a pair of passages communicating with said cylinder, a passage connecting said other passages, a check valve for permitting flow in one direction through said connecting passage but preventing flow in the opposite direction, a piston movable in said cylinder 25 to control said pair of passages, the entrances to said pair of passages from said cylinder being longitudinally spaced along the said cylinder.
- 30 8. The combination with a compressor and a driving motor therefor, of unloading means for said compressor, movable means adapted when in one position to obstruct operation of the unloading means and in another position to permit operation of the unloading means, a control for the flow of motive medium to said motor mechanically connected to said movable means so that movement of the latter to permit operation of the unloading means shifts said control in 35 one direction and movement to obstruct operation of the unloading means shifts said control in the opposite direction.
- 40 9. The combination with a compressor and a driving motor therefor, of unloading means for said compressor, movable means adapted when in one position to obstruct operation of the unloading means and in another position to permit operation of the unloading means, a control for the flow of motive medium to said motor having a link connection to said movable means so that movement of the latter to permit operation of the unloading means shifts said control in one direction and movement to obstruct operation of the unloading means shifts said control in 45 the opposite direction.
- 50 10. The combination with a compressor and a driving motor therefor, of unloading means for said compressor including means for conducting actuating medium to said unloading means, a movable member a portion of which is disposed in said conducting means when in one position so as to obstruct flow of actuating medium to said unloading means and when in another position permits flow of actuating medium to said unloading means, and a control for said motor mechanically connected to said movable member so that movement of the latter to permit operation of the unloading means shifts said control in the opposite direction. 55
- 60 11. The combination with a compressor and a driving motor therefor, of unloading means for said compressor, means forming a yielding obstruction to the operation of the said unloading means, and a control for said motor mechanically connected to said yielding means so that the yielding of the latter to permit operation of the unloading means shifts said control. 65
- 70 12. The combination with a compressor, a driving motor therefor and a receiver, of fluid pressure operated unloading means for said compressor, a conduit for supplying pressure fluid from the receiver to the unloading means to actuate the same, means intermediate the ends of the conduit forming a yielding obstruction to the flow of such fluid to the unloading means, and a control for said motor mechanically connected to said yielding means so that the yielding of the latter to permit flow of actuating fluid to the unloading means shifts said control. 75
- 75 13. The combination with a compressor, a driving motor therefor, and a receiver, of fluid pressure operated unloading means for said compressor, a conduit for supplying pressure fluid from the receiver to the unloading means to actuate the same, a member necessarily movable to permit flow of fluid through said conduit, and a motor controlling element mechanically connected to said movable member so that movement of the latter to permit flow of fluid to the unloading means shifts said controlling element. 80
- 80 14. A controlling mechanism comprising a cylinder having a piston therein, means forming a pair of passages communicating with said cylinder, a by-pass connecting said passages, means permitting fluid flow in one direction through said by-pass but preventing flow in the opposite direction, and vent means associated with said cylinder, said piston being movable in said cylinder to a position to permit fluid flow through one of said passages and through the by-pass to the other passage, and movable to another position to connect the latter passage with said vent means. 85
- 90 15. The combination with a compressor provided with a driving motor, of controlling mechanism therefor comprising controlling means for said motor, pressure fluid 95
- 100
- 105
- 110
- 115
- 120
- 125

actuated unloading means for said compressor, a conduit for leading pressure fluid to said unloading means, controlling mechanism interposed in said conduit comprising a
5 movable element having a surface subject to fluid pressure, said controlling mechanism having a fluid supply port controlled by movement of said element so that in one position the flow of fluid to said unloading
10 means is obstructed and in another position the flow is permitted, and a vent port also controlled by movement of said element so as to vent upon predetermined movement of said element the fluid previously supplied to said unloading means, said element being mechanically connected to said motor contr lling means. 15

In testimony whereof I affix my signature.

FRED D. HOLDSWORTH.
